PAPERING MACHINE

Harry D. Kneller, Brookfield, Ill.

Application September 12, 1938, Serial No. 229,563

18 Claims. (Cl. 91—15)

One object of my invention is to provide a papering machine which is durable and comparatively inexpensive to manufacture and simple to operate.

5 Another object is to provide a papering machine in which the paste is applied to the wallpaper in the form of a thin film, there being a reservoir for paste, with a paste roller rotatable therein and arranged relative to a roll of paper 10 being unrolled, so that the back of the paper passes thereover.

Another object is to provide wiper mechanism 15 so associated with the paper and paste, or paste-applying roller, that a film of the proper thickness of paste on the paper is insured.

Another object is to provide a traction roll around which the paper travels, and means to rotate the traction roll so as to propel the paper through the machine.

20 Still another object is to provide a papering machine in which a main clamp is mounted for receiving the initial end of a strip of paper from the roll of wall paper, after which, upon operation of the traction roll, the strip of paper is 25 fed into a compartment of the machine in a corrugated formation and held against accidental pasting of the corrugations together by a series of separators.

20 A further object is to provide weight rods 30 coactable with the strip of paper for causing it to assume such corrugated formation within the cabinet, the separators and weight rods being automatically moved to their operative positions by operation of the traction roll.

35 A further object is to provide a yoke within the cabinet, having an auxiliary clamp carried thereby and adapted to coact with the paper after it has been folded in corrugated formation within the cabinet, the separators and weight rods being 40 automatically moved to their operative positions by operation of the traction roll.

45 A further object is to provide a yoke within the cabinet, having an auxiliary clamp carried thereby and adapted to coact with the paper after it has been folded in corrugated formation in the cabinet, to retain the initial end of the next strip of paper after the first strip has been severed and is ready to be applied to the wall.

50 Still a further object is to provide a trimmer roll and a trimmer disc coacting therewith, whereby the edge of the paper is automatically trimmed as it is fed through the machine by the traction roll or the paper can be split thereby.

Further objects are to provide means for releasing the weight rods at proper times for co-

action with the strip of paper, means to raise the weight rods and swing them to an inoperative position and means to insure that each end of each weight rod will move downwardly at the same speed, so that the weight rods are not tilted 5 in the machine, and thus binding of the rods is avoided.

Still further objects are to provide modified constructions in which the wallpaper has applied thereto a film of paste and the paper may be 10 merely withdrawn from the machine and thereupon applied to the wall or withdrawn onto a table.

With these and other objects in view, my invention consists in the construction, arrangement and combination of the various parts of my papering machine whereby the objects contemplated are attained, as set forth more in detail in my specification, pointed out in my claims and illustrated in the accompanying drawings, in 15 which

Fig. 1 is a vertical sectional view through my machine, the section being taken on approximately the line 1—1 of Fig. 4;

Fig. 2 is a horizontal sectional view on line 25 2—2 of Fig. 1, and shows a plan view of the mechanism within the cabinet of my papering machine;

Figure 2^a is an enlarged sectional view on the line 2^a—2^a of Figure 2.

Fig. 3 is a vertical sectional view on the line 3—3 of Fig. 1, showing operative parts within a compartment at the left end of the cabinet;

Fig. 4 is a vertical sectional view on the line 4—4 of Fig. 1, showing the paper pasting and 35 handling mechanism within the cabinet;

Fig. 5 is a vertical sectional view on the line 5—5 of Fig. 1, showing the operative mechanism within an end compartment at the right hand end of the cabinet;

Fig. 6 is an enlarged sectional view similar to the upper portion of Fig. 4, showing the parts in different positions;

Fig. 7 is a vertical sectional view similar to the right hand portion of Fig. 4, showing the parts 45 in still another position;

Fig. 8 is an end elevation, partly in section, showing modified constructions substituted for some of the parts shown in the preceding figures;

Fig. 9 is a fragmentary perspective view on an 50 enlarged scale, showing an auxiliary clamp mounted on a yoke of the machine;

Fig. 10 is a vertical sectional view of a modified form of paper machine, showing it in use, and

Fig. 11 is a sectional view of still another modified form of machine.

On the accompanying drawings, I have used the reference character C to indicate a cabinet.

The cabinet C includes a front wall 10 and a back wall 12. The wall 10 has an openable portion 10a (see Fig. 4) to permit access to the cabinet for inserting rolls of wallpaper 13 therein. Within the cabinet C, I provide a trough 14 adapted to contain paste 15. The paste 15 is preferably of the consistency commonly used when brushing the paste onto the wallpaper by hand.

Journaled for rotation in the trough 14, so that its lower portion dips into the paste 15, is a paper-pasting or paste-applying roll 16. The roll of paper 13 is adapted to be supported in a pair of pivoted arms 17, so that the weight of the paper roll causes it to contact at all times with the pasting roll 16. It is therefore obvious that, as a strip of paper 13a is unrolled from the roll 13, a film of paste will be applied thereto by simultaneously rotating the roll 16 in the proper direction.

For unrolling the roll 13, I provide a traction roll 18. The strip of paper 13a passes over the traction roll and then over a trimmer roll 19. The rolls 16, 18 and 19 are rotated simultaneously by a belt drive comprising pulleys 16a, 18a and 19a, and a belt 20, as shown in Fig. 5. The roll 18 is rotated by a crank 18b (see Fig. 1). The crank 18b is adapted to be rotated by hand although, obviously, other means such as an electric motor could be provided for this purpose.

To insure that too heavy a film of paste is not applied to the strip 13a, I provide wiper blades 21 and 22. These, as shown in Fig. 4, are pivotally mounted and urged to engage the pasting roll 16 and the paper strip 13a by springs 21a and 22a. The blades 21 and 22, as illustrated in Figs. 1 and 2, are serrated, which I find effectively wipes the desired excess of paste from the roll and strip in a desirable manner.

For coaction with the trimmer roll 19 I provide one or more trimmer discs 23. These are pivotally supported on a rod 24 and urged to engage the trimmer roll 19 by springs 24a. They may be set at different distances apart so as to trim the paper to any width desired.

The cabinet C is divided into three compartments, which are shown as C1, C2 and C3, and in Figs. 1 and 2 are respectively the left-hand, center and right-hand compartments. These compartments are shown respectively in Figs. 3, 4 and 5.

The parts 14 to 24, thus far described, are located in the central compartment C2. Also located in this compartment is a yoke 25, separator rods S1, S2 and S3, weight rods W1, W2 and W3, and a main clamp 26-27. The yoke 25 is inverted U-shape, as shown in Fig. 1, with the lower ends of its arms pivoted to links 28. The links 28 are secured to a shaft 29 which extends into the compartment C3 and has thereon a lever 30.

The lever 30 is connected by a link 31 with an operating lever 32, which can be manipulated by the operator extending his hand through an opening 33 of the front wall 10 of the cabinet C. By pulling outwardly on the lower end of the lever 32, the rock shaft 29 is rotated clockwise for lowering the yoke 25 to the position desired. The yoke 25 is normally retained in the position shown in Fig. 4 by springs 34. It can be swung rearwardly (toward the rear wall 12) by the

operator during the operation of the machine. During such operation, a lid 35 of the cabinet C is left in open position as shown in Figs. 3, 4 and 5.

The yoke 25 includes clamp members 36 which are preferably rubber-headed pins slidably mounted in a cross bar 37. Springs 36a are interposed between the heads of the pins 36 and the cross bar 37 to aid in the clamping action as will hereinafter be obvious. The cross bar 37 is slideable relative to brackets 38 which are secured to the yoke 25, as shown in Fig. 9, a pair of pins 39 and 40 in a slot 41 serving as the slideable connection. The cross bar 37 is normally retained in raised position by a spring 42 at each end of the bar. The bar can be lowered manually and the pins 40 swung into bayonet extensions 43 of the slots 41 when it is desirable to cause the clamp elements 36 to engage the yoke 25.

The separator rods S1, S2 and S3 are also yoke-shaped, as shown in Fig. 1 with their lower ends secured to rock shafts 44 as shown in Fig. 5. The rock shafts 44 are extended into the compartment C3 and terminate in levers 45. The levers 45 are adapted to be actuated by links L1, L2 and L3, which are normally held against a stop bar 46 by springs 47. Each link is provided with a first shoulder 48 and a second shoulder 49. The shoulders 48 and 49 are adapted to engage the stop bar 46, the springs 47 tending to retain such engagement.

The links L1, L2 and L3 are adapted to be released by cams 50, 51 and 52. Each cam is in alignment with its particular link, as shown in Fig. 1, and has a cam lobe to engage the upper end of the link and release the shoulder 48 from the stop bar 46 whereupon the link is pulled upwardly by its spring 47 and the second shoulder then engages the stop bar. The links L1 and L2 are shown with their shoulders 49 and 48 respectively engaging the stop bar in Fig. 5.

The main clamp 26-27 consists of the bar 26 and sliding pins 27 having rubber covered heads on their lower ends. The pins 27 slide in a bar 53, which is stationarily mounted on the back wall 12 of the cabinet C (see Fig. 4). The bar 26 is supported slidably by rods 54, which slide in a stationary cleat 55 on the back wall 12. Interposed between the bar 26 and the cleat 55 are springs 26a which normally retain the clamp bar 26 raised and in engagement with the pins 27. Springs 27a on the pins 27 also aid in resiliently clamping the strip 23a in the main clamp 26-27.

The rods 54 extend downwardly and connect with levers 56 extending from a rock shaft 57. The rock shaft 57 extends into the compartment C3 (see Fig. 5) and terminates in a lever 58. The lever 58 is adapted to be raised by depressing a foot pedal 59 which is pivoted at 60. An opening 61 is provided in the front wall 10 from which the pedal 59 projects.

The weight rods W1, W2 and W3 are adapted to be normally supported by rod hooks 62. The rod hooks 62 are provided with individual hook elements for the weight rods and are pivoted at 63 to levers 64. The levers 64 have stop flanges 65 to engage the rear ends of the rod hooks 62 and swing the rod hooks, together with the weight rods to the position of Fig. 7 when a rock shaft 66 on which the levers 64 are mounted is rotated clockwise. When the rock shaft is rotated counterclockwise, the rod hooks 62 are first lowered until they strike stop pins 67, as shown by solid lines in Fig. 6, and are then moved horizontally rearwardly to the dotted position 75

upon further counterclockwise rotation of the rock shaft 66. The rock shaft 66 extends into the compartment C3 as shown in Fig. 5 and terminates in a lever 68 which may be manipulated for rocking the shaft.

The weight rods W1, W2 and W3 are adapted to be released from their supported position by levers 69. In Fig. 6, the weight rod W1 has already been so released by clockwise rotation of a rock shaft 70 from which the lever 69 depends. For rocking the shaft 70 I extend it into the compartment C3 as shown in Fig. 5 and provide thereon a crank pin 71. The crank pin 71 overlies one end of a lever 72 which is pivoted at 73. The other end of the lever 72 cooperates with a cam 74. The cam 74 is mounted on a camshaft 75, the cams 50, 51 and 52 being also mounted on this shaft.

The shaft 75 is rotated automatically by rotation of the traction roll 18 by step-down gearing 76. The gearing 76 is frictionally connected to the camshaft 75 as by being interposed between a collar 76a and a friction spring 76b (see Figure 2a). The friction spring is interposed under tension between the gearing and the cam 74 on the camshaft 75.

The camshaft 75 includes a dial 77 for indicating the number of feet in the strip of paper 13a. The dial 77, together with the cams 50, 51, 52 and 74, may be rotated relative to the gearing 76 by the operator engaging the dial and rotating it against the friction of the spring 76b. Thereafter the cams will be rotated by the gearing. The purpose of this arrangement is so that the dial 77 can be set with its zero point coincident with a pointer 77a (see Fig. 2), at the beginning of each strip of paper and the cams will thereafter operate in proper sequence and at the proper times during the operation of the machine.

To prevent the weight rods from wiping the paste off the strip 13, I provide spaced enlargements 78 thereon, as shown in Fig. 2.

The weight rods are adapted to fall on the strip 13a as shown in Fig. 6 and insure that the strip will depend properly within the compartment C2 so that it can be folded in a corrugated fashion and supported by the separators S1, S2 and S3 as shown in Fig. 7. The weight rod W1 is shown dotted in the lower portion of the figure merely to indicate its position prior to being raised by mechanism which I will now describe.

The raising mechanism for the weight rods consists of carriers 79 which are provided with notches to receive the weight rods. The carriers 79 are provided with hubs 79a slidably on vertical rods 79b. Means for raising the carriers is provided in the form of pins 80 extending from them through vertical slots 81 into the compartments C1 and C3, as shown in Fig. 5. The pins 80 are connected to cables 82 which extend over pulleys 83 and 84 and are anchored at 85. Journal pins 86 for the pulleys 83 are stationary relative to the cabinet C while the pulleys 84 are carried by arms 87 on a rock shaft 88. The portion of the rock shaft 88 in the compartment C3 is provided with a lever 89, which can be pulled outwardly through the slot 33, thereby swinging the arms 87 and the pulleys 84 downwardly to effect raising of the pins 80 and the carriers 79. The particular arrangement of pulleys 83 and 84 and anchorage point 85 effect considerable movement of the carriers 79, with a comparatively short swing of the lever 89.

In Fig. 8, I show a modified construction

which insures that the ends of the weight rods will move downwardly at the same speed. The weight rods are provided adjacent each end with pinions 90 cooperating with racks 91. Straps 92 engage the weight rods to retain the pinions 5 in mesh with the racks. I still provide the same carriers 79 for raising the weight rods, but after the rods are raised as high as the carriers will go they are swung upwardly to a position out of the way by arms 92. The arms 10 92 are mounted on a rock shaft 93 which has an operating lever 94 located in the compartment C1. The upper ends of the racks 91, it will be noted, are arcuate, and a hook member 95 is provided for each weight rod. As the 15 weight rods are swung upwardly by the arms 92, they lift the hooks and finally drop into position for holding the weight rods whereupon the lever 94 can be returned to its inoperative position.

For releasing the weight rods progressively, I provide a single cam 96, taking the place of the three cams 50, 51 and 52. The cam 96 is provided with progressively higher lobes 59a, 51a and 52a, for the purpose of raising the left hand 25 end of a lever 97 pivoted at 98. The other end lowers a bar 99 having pins 100, 101 and 102 to engage the hooks for the weight rods W1, W2 and W3 progressively thus releasing them at different times during the rotation of the cam 96. 30

Also, in Fig. 8, I show a modified construction for the paper pasting roll of my machine. The roll in this figure is indicated at 16a and a second roll 16b is rotatable therebelow. The rolls 16a and 16b are rotated in opposite directions 35 by suitable gearing and a small roll 16c tends to cause the paste 15 to pile up as at 15a and be thus effectively transferred to the roll 16a. In this way a relatively deep trough 14a of large capacity can be used and initially filled to the 40 line indicated at 16d on the paste-applying roller 16a yet paste will be effectively applied to the roll 16a even when the level of the paste is low as shown in this figure.

In Fig. 10, I show a modified construction 45 in which a casing 104 has contained therein a roll of paper 113 passing over a pasting roll 116. A trough 114 is provided for the paste 115 and a strip 113a of the wallpaper may be grasped 50 by the operator 105 and pulled outwardly through a slot 106 in the casing 104. A roller 107 is provided geared to the roller 116 by gears 120. The paper extends under the roller 107 so that it is not dragged across the upper edge of 55 the slot. The strip 113a can be applied directly to the wall surface indicated at 108 and trimmed off at its lower end after the strip has been pasted on the wall. The casing 104 serves as a convenient means for the operator 105 to 60 stand on during the papering operation. A door 109 is provided through which access may be had to the interior of the casing 104 for placing a fresh roll 113 therein.

If it is desirable to use a table such as T in 65 Fig. 11, on which to work, an arrangement can be provided consisting of a pasting roll 216, trough 214, and idler rolls 218 and 219 supported on the table. The rolls 216 and 218 may be geared together by gears 220 so that they 70 rotate simultaneously at the proper relative speeds as the paper strip 213a is pulled over the roller 219 and across the top of the table T. Pivoted arms 217 are provided for supporting the roll of paper 213. On the table T, the strip 75

213a may be trimmed and cut to length in the ordinary manner.

The top 35 of the cabinet C may be closed and used when desired like a table top for pasting and trimming operations.

Practical operation

In the operation of my paper pasting machine, first of all the operator must have the hook rods 62 in the raised position shown in Fig. 7 and the separators S1, S2 and S3 swung forwardly as shown in Fig. 4. He then places the roll of paper 13 in position supported by the arms 17 and threads the strip 13a around the traction roll 18, over the trimmer roll 19 and then into the clamp 36 of the yoke 25. The clamp is in open position as in Figs. 4 and 9 and the initial end of the strip 13a is passed therethrough to extend about an inch beyond the yoke. The clamp bar 37 is then lowered and retained in lowered position by the pins 40 engaging in the bayonet portions 43 of the slots 41. In this position, the springs 36a are under compression thereby clamping the strip in position.

The yoke 25 is then lowered by pulling outwardly on the downwardly extending end of the lever 32 and is swung rearwardly by the operator engaging the yoke or bar 37, finally assuming a position approximately as shown in Fig. 7. (The separators S1, S2 and S3, however, are in the forward position as in Fig. 4.) The foot pedal 59 is then depressed for opening the main clamp 26-27 and the extending initial end of the strip 13a enters the main clamp. Thereupon the pedal 59 is released for closing the main clamp and the auxiliary clamp on the yoke 25 is opened. The yoke may then be swung forwardly to the position of Fig. 4, so that it remains out of the way until it is necessary to use it again.

The foregoing description of the operation is for preparing the machine for use. I will now describe an operating cycle of the machine.

The rod hooks 62 are swung from the position of Fig. 7 to the full line positions of Figs. 4 and 6 by swinging the lever 68 in the compartment C3 counterclockwise. The dial 71 is set at zero and the operator commences to turn the crank 18b for feeding the strip 13a through the machine. Immediately the cam 74 lifts the crank pin 71 for swinging the lever 69 to the position shown in Fig. 6, thus releasing the weight rod W1 from the rod hooks 62.

As the traction roll 18 is further rotated, the strip 13a will depend between the main clamp 26-27 and the separators S1, S2 and S3, as shown by solid lines in this figure, and will be carried downwardly by the weight rod W1. During such downward movement, the cam 50 will cause the shoulder 48 of the link L1 to be released as in Fig. 5 so that the spring 47 for this link will pull the link upwardly until the shoulder 49 engages the stop bar 46. This will swing the separator 51 to the dotted position shown in Fig. 6 so that one corrugation of the strip 13a is then depending between the separator 51 and the main clamp. Thereafter during further rotation of the operating crank 18b the weight rod W2 will be released, the separator S2 will be swung rearward, the weight rod W3 will be released and the separator S3 will be swung rearward. By this time the dial 71 will register in the neighborhood of twelve feet as each loop or corrugation of the strip 13a is approximately four feet long.

If the paperhanger desires a twelve-foot piece of paper, he may now stop rotation of the crank 18b. The next step is to slide the rod hooks 62 back to the dotted position of Fig. 6, so that the rods can be raised in front of their respective hooks thereof. The lever 89 is then pulled outwardly through the slot 33 for elevating the rod-raising elements 79 whereupon they will assume positions in front of their hook elements of the rod hooks 62. While in this position, the lever 68 is rotated clockwise for first shifting the hooks of the elements 62 to the full line position of Fig. 6 and then elevating them to the position of Fig. 7 for subsequent repetition of the cycle of operation.

All three of the separators S1, S2 and S3 are then swung forwardly to the position of Fig. 7 for pasting the corrugations of the strip 13a together. This is done by pressing rearwardly on the upper ends of the links L1, L2 and L3 so that their shoulders 49 are released from the stop bar 46 and the springs 47 then swing the separators to the desired position.

The next step is to swing the yoke 25 forwardly as in Fig. 7 to a position adjacent the point indicated by the arrow 103 and lower the clamp bar 37 so as to clamp the paper in the auxiliary clamp of the yoke. A knife can then be passed along a line indicated by the arrow 103 to sever the strip 13a from the remainder of the roll 13. The yoke 25 may then be permitted to swing forwardly to the position of Fig. 4, where it is out of the way and the corrugated strip 13a lifted out of the machine and applied to the wall. The corrugated formation of the strip permits ready handling of the paper by the paperhanger during this process, as well as making it unnecessary to have the cabinet half as tall as the strip of paper is long as would be necessary if the separators and their associated mechanism were not provided.

If it is desirable to have less than twelve feet of paper, for instance ten feet, then the operator merely stops turning the crank 18b when the dial 71 registers ten feet in which case the weight rod W3 would only be about half way down. If six feet of paper are required only the weight rods W1 and W2 are released and the weight rod W2 is only about half way down at the time of severance of the strip from the roll. Thus it is obvious that any desired length of strip can be taken from the machine and if longer strips are desired the machine can be designed to release additional weight rods and to include additional separators.

The yoke 25 may now be swung forwardly and downwardly again to clamp the initial end of the next strip in the main clamp. The yoke clamp is then unclamped and the yoke permitted to swing forward again to the position of Fig. 4 whereupon the cycle of operations described is repeated.

The operation of the device shown in Fig. 10 is believed obvious. After one strip of paper is applied to the wall, the casing 104 may be shifted along the wall and the next applied and so on. With the apparatus shown in Fig. 11, a paperhanger accustomed to working on a table top can still do so and the apparatus merely serves as a convenient automatic means to apply the paste to the paper without the necessity of having to brush the paste on the paper.

From the foregoing description, it is obvious that I have provided a papering machine in which the wallpaper may have properly applied

thereto a film of paste and the machine manipulated so that the paper is supported in the machine in a manner which avoids all danger of the folds or corrugation becoming all pasted together and for convenience in the application of the strip to the wall after it is removed therefrom. The paper can be trimmed during the pasting operation and the paperhanger need not measure the paper, as the dial 77 at all times indicates just how much paper is being fed into the strip to be removed from the machine. The mechanism is easily operated and after a few minutes' instruction and practice one man can use my machine and paper a room in approximately the time that it usually takes two men to do so where the paperhanger has a helper applying paste to the paper by the brush method.

Some changes may be made in the construction and arrangement of the parts of my apparatus without departing from the real spirit and purpose of my invention. Accordingly, it is my intention to cover by my claims such modified forms of structure or use of mechanical equivalents which may be reasonably included within their scope.

I claim as my invention:

1. In a papering machine, a cabinet, a paste reservoir therein, a paper pasting roll rotatable in said reservoir, means for supporting a roll of paper to be unrolled, a serrated wiper blade engaging said paper pasting roll, a traction roll, said strip of paper passing over said pasting roll and then said traction roll whereby said paper is propelled by rotation of said traction roll, a second serrated wiper blade engaging said paper at a point between said pasting and traction rolls, means for rotating said traction roll, a yoke, a clamp carried thereby, a main clamp adapted to receive the initial end of said strip of paper, said yoke being pivoted and thereby movable to a position for guiding said movable end to said main clamp, weight rods, pivotally mounted supporting hooks therefor, pivotally mounted separators for supporting said strip during the propelling thereof, means responsive to rotation of said traction roll for spacing said separators and releasing said weight rods from said supporting hooks whereby said strip will assume a corrugated position supported on said separators, means for raising said weight rods and returning them to a position supported on said supporting hooks, said separators being swingable on their pivots toward each other for pasting the folds of said corrugated strip together, said yoke being thereupon engageable with said strip adjacent said separators whereby to permit severance of the strip from the roll of paper at a point between the yoke and the separators.

2. In a papering machine, a cabinet, a paste reservoir therein, a paper pasting roll rotatable in said reservoir, means for supporting a roll of paper to be unrolled, a traction roll, said strip of paper passing thereover to be propelled by rotation thereof, means for rotating said traction roll, a pivotally mounted yoke, a clamp carried thereby, a main clamp adapted to receive the initial end of said strip of paper, said yoke being movable about its pivot to a position for guiding said movable end into said main clamp, weight rods, pivotally mounted supporting hooks therefor, pivotally mounted separators for coaction with said strip during the propelling thereof, means responsive to rotation of said traction roll for spacing said separators and releasing said weight rods whereby said strip will assume a corrugated position supported on

said separators, means for raising said weight rods and returning them to a position supported on said supporting hooks, means for swinging said separators toward each other for pasting the folds of said strip, when corrugated together, 5 said yoke being thereupon engageable with said strip adjacent said separators whereby to permit severance of the strip from the roll of paper at a point between the yoke and the separators.

3. In a papering machine, a cabinet, a paste 10 reservoir therein, a paper pasting roll rotatable in said reservoir, means for supporting a roll of paper to be unrolled, a traction roll, said strip of paper passing thereover to be propelled by rotation thereof, means for rotating said traction 15 roll, a main clamp adapted to receive the initial end of said strip of paper, weight rods, pivotally mounted supporting hooks therefor, pivotally mounted separators for coaction with said strip during the propelling thereof, means responsive 20 to rotation of said traction roll for spacing said separators and releasing said weight rods whereby said strip will assume a corrugated position supported on said separators, means for raising said weight rods and returning them to a position supported on said supporting hooks, and 25 means for swinging said separators toward each other for pasting the folds of said strip, when corrugated, together.

4. In a cabinet, a paper pasting roll, means for supporting a roll of paper to be unrolled for passage over said paper pasting roll to receive a film of paste therefrom, a traction roll for propelling a strip of paper being unrolled from said roll of paper by rotation of said traction roll, trimming 30 means for said strip, means for rotating said traction roll and operating said trimming means, a main clamp adapted to receive the initial end of said strip, a yoke, an auxiliary clamp thereon to carry said initial end of said strip to said 35 main clamp, weight rods, movable supporting hooks therefor, movably mounted separators for coaction with said strip during the propelling thereof, means responsive to rotation of said traction roll for spacing said separators and 40 moving said supporting hooks to thereby release said weight rods whereby said strip will assume a corrugated position within said cabinet, means for raising said weight rods and returning them to a position supported on said supporting hooks, 45 means for moving said separators toward each other for pasting the folds of said strip, when corrugated, together, said auxiliary clamp of said yoke being thereupon engageable with said strip adjacent said separators whereby to permit severance of the strip from the roll of paper at a 50 point between the yoke and the separators.

5. In a cabinet, a paper pasting roll, means for supporting a roll of paper to be unrolled for passage over said paper pasting roll to receive 60 a film of paste therefrom, a paste reservoir, a paste roll therein for picking up a film of paste therefrom, said paper pasting roll having its lower surface adjacent the upper surface of said paste roll for transfer of paste from said paste 65 roll to said paper pasting roll, a clamp adapted to receive the initial end of said strip, weight rods, movable supports therefor, movable separators for supporting coaction with a strip of paper unrolled from said roll of paper, means for 70 moving and thereby spacing said separators from each other and for moving said supports and thereby releasing said weight rods whereby said strip will assume a corrugated position within the cabinet, means for raising said weight rods 75

and returning them to position supported on said supports and means for moving said separators toward each other for pasting the folds of said corrugated strip together.

5 6. In a cabinet, a paper pasting roll, means for supporting a roll of paper to be unrolled for passage over said paper pasting roll to receive a film of paste therefrom, a clamp adapted to receive the initial end of said strip, weight rods, 10 movable supports therefor, movable separators for supporting coaction with a strip of paper unrolled from said roll of paper, means responsive to movement of said strip through the machine for moving and thereby spacing said separators 15 and for moving said supports to thereby release said weight rods in consecutive order whereby said strip will assume a corrugated position within said cabinet and means for raising said weight rods and returning them to position supported 20 on said supports.

7. In a papering machine, a cabinet, a paste reservoir therein, a paper pasting roll rotatable in said reservoir, means for supporting a roll of paper to be unrolled, a serrated wiper blade engaging said paper pasting roll to distribute the film of paste thereon prior to contact therewith of a strip of paper being unrolled from a roll of paper supported on said paper supporting means, a traction roll, said strip of paper passing thereover to be propelled by rotation thereof, means for rotating said traction roll, a yoke, a clamp adapted to receive the initial end of said strip, said yoke being movable to a position for guiding said initial end to said clamp, pivotally mounted separators for supporting coaction with said strip during the propelling thereof, a plurality of weight rods thereabove, means responsive to rotation of said traction roll for spacing said separators and releasing said weight 35 rods between the separators whereby said strip will assume a corrugated position within said cabinet and means for swinging said separators toward each other for pasting the folds of said corrugated strip together.

45 8. In a papering machine, a cabinet, a paste reservoir therein, a paper pasting roll rotatable in said reservoir, means for supporting a roll of paper to be unrolled, a traction roll for propelling a strip of paper by rotation of said traction roll, means for rotating said traction roll, movable separators for coaction with said strip during the propelling thereof, weight rods, means responsive to rotation of said traction roll for moving said separators to positions spaced from each other 50 and for positioning said weight rods between said separators whereby said strip will assume a corrugated position supported by said separators within said cabinet and means for moving said separators toward each other for pasting the 55 folds of said corrugated strip together.

9. In a papering machine, a cabinet, a paste reservoir therein, a paper pasting roll rotatable in said reservoir, means for supporting a roll of paper to be unrolled, a traction roll for propelling a strip of paper from a roll of paper supported on said paper supporting means, means for rotating said traction roll, movable separators for coaction with said strip during the propelling thereof, weight rods and means responsive to 65 rotation of said traction roll for moving said separators to spaced relative positions and for positioning said weight rods on said strip between said separators whereby said strip will assume a corrugated position supported by said separators within said cabinet.

10. In a papering machine, a paste reservoir, a passing roll therein, a traction roll for a strip of paper passing over said pasting roll and then said traction roll whereby said paper is propelled by rotation of said traction roll, means for rotating said traction roll, a yoke, an auxiliary clamp carried thereby, a main clamp adapted to receive the initial end of said strip, said auxiliary clamp and yoke being movable to a position for guiding said initial end into said main clamp, weight rods, supporting hooks therefor, separators, means responsive to rotation of said traction roll for releasing said weight rods from said supporting hooks and permitting them to fall on said strip between said separators where- 15 by said strip will assume a corrugated position supported on said separators, means for raising said weight rods and returning them to positions supported on said supporting hooks, said auxiliary clamp being thereupon engageable with said strip to permit severance of the strip from the roll of paper at a point between the yoke and the main clamp.

11. In a papering machine, a cabinet for a roll of paper supported therein and adapted to be 25 unrolled, means for applying paste to a strip of paper being unrolled from the roll of paper, a traction roll for propelling said strip of paper by rotation of said traction roll, a clamp adapted to receive the initial end of said strip, weight 30 rods, guides for said weight rods, said guides having racks provided with curved portions and said weight rods having pinions coacting therewith to retain said weight rods against binding, movable supporting arms for said weight rods, 35 spaced separators in said cabinet, means responsive to rotation of said traction roll for periodically releasing said weight rods whereby said strip will assume a corrugated position supported on said separators and means for raising said 40 weight rods and moving them by said supporting arms to positions supported on said curved portions of said racks.

12. In a papering machine, a cabinet, a paper pasting roll therein, means for supporting a roll 45 of paper to be unrolled for passage over said paper pasting roll to receive a film of paste therefrom, a traction roll for propelling a strip of paper being unrolled from said roll of paper and passing around said traction roll by rotation of said traction roll, means for rotating said traction roll, movable separators for coaction with said strip during the propelling thereof, weight rods above said separators, means responsive to rotation of said traction roll for spacing 50 said separators and for releasing said weight rods whereby said strip will assume a corrugated position supported on said separators within said cabinet and means for moving said separators toward each other for pasting the folds of said 55 corrugated strip together.

13. In a papering machine, a cabinet, a paper pasting roll therein, means for supporting a roll of paper to be unrolled for passage over said paper pasting roll to receive a film of paste therefrom, a traction roll for propelling a strip of paper being unrolled from a roll of paper by rotation of said traction roll and separators and weight rods for periodic coaction with said strip during the propelling thereof by said traction 70 roll whereby said strip will assume a corrugated position supported thereon.

14. In a papering machine, a cabinet, means therein for supporting a roll of paper to be unrolled, means for applying a film of paste thereto, 75

a traction roll for propelling a strip of paper being unrolled from said roll of paper by rotation of said traction roll, means for rotating said traction roll, weight rods, rod supports therefor, 5 separators within said cabinet for supporting said strip, means responsive to rotation of said traction roll for releasing said weight rods from said rod supports at spaced intervals whereby said strip will assume a corrugated position supported 10 on said separators and means for raising said weight rods and returning them to positions supported by said rod supports.

15. In a paper machine, a cabinet, means for supporting a roll of paper to be unrolled, means 15 for applying a film of paste thereto, weight rods, supporting hooks therefor, separators for supporting said strip, means for releasing said weight rods whereby said strip will assume a corrugated position within said cabinet, and 20 means for raising said weight rods and returning them to positions supported by said supporting hooks.

16. In a papering machine, a cabinet, means for supporting a roll of paper to be unrolled, 25 means for applying a film of paste thereto, a clamp adapted to receive the initial end of said strip, weight rods, rod supports therefor, separators for supporting said strip, said clamp being spaced from one of said separators and 30 means for releasing said weight rods from said rod supports to positions between said separators and between said one of said separators and said

clamp whereby said strip will assume a corrugated position within said cabinet.

17. In a papering machine, a cabinet, a paste reservoir therein, a paper pasting roll rotatable in said reservoir, means for supporting a roll of paper to be unrolled, a traction roll for propelling a strip of paper passing thereover upon rotation of said traction roll, means for rotating said traction roll, a yoke, a clamp carried thereby, a stationary main clamp adapted to receive the initial 10 end of said strip, said yoke being movable to a position for guiding said initial end to said main clamp, means responsive to rotation of said traction roll for causing said strip to assume a corrugated position within said cabinet and means 15 for pasting the corrugations thereof together at the top whereupon said corrugated strip is removable from said cabinet for application to a wall.

18. In a papering machine, a cabinet, means 20 for supporting a roll of paper to be unrolled and for applying a film of paste thereto, a traction roll for propelling a strip of paper by rotation of said traction roll, a stationary clamp adapted 25 to receive the initial end of said strip, means responsive to rotation of said traction roll for causing said strip to assume a corrugated position within said cabinet and beginning at said stationary clamp and means for pasting the corrugations thereof together at the top of said 30 corrugated strip.

HARRY D. KNELLER.
